EDGE-BEVELING MACHINE.

1,368,263.

Specification of Letters Patent. Patented Feb. 15, 1921.

Application filed September 27, 1919. Serial No. 326,889.

To all whom it may concern:

Be it known that I, ALBERT F. JOHNSTON, a citizen of the United States, and a resident of Toledo, in the county of Lucas and State of Ohio, have invented a certain new and useful Edge-Beveling Machine; and I do hereby declare the following to be a full, clear, and exact description of the invention, such as will enable others skilled in the art to which it appertains to make and use the same, reference being had to the accompanying drawings, and to the characters of reference marked thereon, which form a part of this specification.

This invention relates to glass working machines and particularly to a machine for beveling the edges of glass plates of circular, elliptical or other curved form.

The object of my invention is the provision of a simple and efficient machine of the character described, which is easy to operate and quickly adjustable to adapt it for grinding bevels on the edges of plates of different curved shapes and sizes.

The invention is fully described in the following specification, and while, in its broader aspect, it is capable of embodiment in numerous forms, a preferred embodiment thereof is illustrated in the accompanying drawings, in which,—

Figure 1 is a side elevation of a machine embodying the invention, with parts broken away and with the work-carrying spindle in vertical position. Fig. 2 is a front elevation of the machine, with portions broken away and with the work-carrying spindle in inclined position. Fig. 3 is a fragmentary detail, with parts in section, of the automatic axial adjusting means for the work-carrying spindle. Fig. 4 is a sectional view of the work holder at the end of the work-carrying spindle. Fig. 5 is an enlarged section on the line 5—5 in Fig. 1, with a part in full, and Fig. 6 is a rear end elevation of the index means for determining the degree of inclination of the work-carrying spindle.

Referring to the drawings, 1 designates the machine base having the upright portions 2 and 3 rising therefrom, with the latter forming, in the present instance, a conical socket-bearing 4 in its top in which the conical journal bearing 5 of a top frame 6 is mounted for horizontal turning movements. The frame 6 is provided with the two axially aligned horizontal arms 7 and 8, which

are hollow throughout their length to receive and form a bearing for the templet shaft 9, which carries a templet 10 at its forward end without the outer end of the arm 7. The shaft 9 has a bevel gear 11 fixed thereto intermediate the arms 7 and 8 and in mesh with a bevel gear 12 of like size on the upper end of a shaft 13, which projects down through the frame 6 and through its journal 5 axially thereof and into the base 65 upright 3 where its lower end is suitably journaled and carries a pulley 14 for receiving power, as hereinafter described.

A tilting frame 15 is mounted above the frame 6 longitudinally thereof for transverse tilting or rocking movements relative thereto, and for such purpose has front and rear leg portions provided with split bearings 16 and 17, respectively, for rotatably receiving and clamping onto the outer ends 70 of the respective frame arms 7 and 8. The forward end of the frame 15 is provided with bearing arms 18 and 19, the former of which projects downwardly and forwardly from the bearing 16 and forms a vertical 80 bearing for the lower end of the work-carrying spindle 20, while the bearing arm 19 projects upward and forward from the bearing 16 or from the forward end of the frame 15 and forms a vertical bearing for a hub sleeve 85 21, which has the upper end of the spindle 20 splined therethrough and is provided at its lower end with a miter gear 22. The gear 22 is in mesh with and driven by a miter gear 23 on the forward end of a shaft 90 24, which is journaled at its forward end portion in the bearing arm 19 and at its rear end portion in a bearing arm 25 projecting upward from the frame 15. The rear end of the shaft 24 is connected by a 95 set of miter gears 26 to a vertical shaft 27, which is journaled in a vertical bearing provided in the frame 15 and is provided at its lower end with a miter gear 28 in mesh with and driven by the gear 11 on the 100 shaft 9.

It is apparent that rotation is communicated from the shaft 13 to the shaft 9 for turning the templet 10 and thence through the shafts 27 and 24 to the work-carrying 105 spindle 20. The speed of driving of the templet 10 should be the same as that of the spindle 20 and for this reason the different miter gears are of like or suitable size for such purpose.

The spindle 20, which is intended to have free rotary and axial movements through its bearings, is provided at its lower end with a work-holding means 29, which, in the present instance, is in the form of a suction cup for holding a work-plate *a* thereto. This suction cup is provided at its lower edge with a gasket 30 against which the work-plate *a* seats, and when a work-plate has been placed in position thereagainst, air is exhausted from the interior of the cup through an exhaust nipple 31, which may be connected to any suitable pump for such purpose, thus causing a firm adhering of the work-plate to the holder, as well understood in the art.

The frame 15 is tilted to present the edge of the work-plate *a* at such an angle to a subjacent grinding wheel or medium 32 as to form the desired bevel, and the frame is clamped and held in this position by a tightening of the split bearings 16 and 17 on the carrying arms of the frame 6. The upper end of the spindle 20 is extended above the sleeve 21 and is provided with weights 33 to exert a desired downward pressure on the spindle. The downward pressure of the spindle 20 is opposed in the major part of the templet 10, which bears upward against a flanged collar 34 on the spindle 20 and acts on said collar to impart predetermined longitudinal movements to the spindle dependent on the shape of the templet. In the present embodiment of the invention, the collar 34 may either be loose or splined on the spindle 20 and has its upper end in ball bearing thrust contact with an adjusting collar 35, which is threaded on the spindle 20 and therefore adapted by a rotary movement thereof relative to the spindle to effect or permit an adjustment of the thrust collar 34 axially of the spindle. The adjusting collar 35 is automatically turned upward on the spindle at a slow predetermined speed to permit a downward feeding of the spindle and work at a speed suitable to compensate for the grinding away of the edge of the work-plate during the beveling action. It is therefore evident that the work-plate *a* does not bear on the grinding member 32 at the full weight or pressure of the spindle but at only a predetermined portion of such weight or pressure as the major portion thereof is borne by the templet 10, and that the turning of the adjusting collar on a threaded portion of the spindle permits a slight downward feeding of the spindle to compensate for the grinding action so that the pressure of the work-plate on the grinding medium is approximately uniform during the entire beveling operation.

The automatic means employed for adjusting or effecting a turning of the collar 35 on the spindle comprises a reciprocating

pawl or detent member 36, which is mounted in the frame 15 for longitudinal reciprocatory movements toward and away from the periphery of the collar 35 and has the end thereof adjacent to the collar adapted to work into a registering one of a plurality of notches 37 provided around the periphery of said collar, whereby to hold the collar against rotation with the spindle 20 when engaged by the detent and thus effect a predetermined upward turning of the collar on the spindle. A bell-crank lever 38 is carried by the frame 15 with its fulcrum stud 39 mounted in a horizontal slot 40 in said frame for horizontal adjustment. One arm of this lever extends downward and is yieldingly connected to the rear end of the detent 36 to impart yielding reciprocatory movements to said detent when the lever is rocked and the other arm of the lever extends rearward, in the present instance, and is connected to a post 41, which is carried in vertical position by the frame 15 for yielding vertical or longitudinal movements relative thereto, and has its upper end provided with a roller 42 bearing upward against a cam 43 on the shaft 24. The post 41 extends down within a socket in the frame 15 and has a yielding upward pressure exerted thereagainst by a coiled compression spring 44 mounted in said socket. A pivot stud 45 projects from a side of the post 41 into a longitudinal slot 46 in the horizontal lever arm so as to impart rocking movements to the lever when the post 41 is vertically moved and to permit a horizontal adjustment of the lever relative to the post to vary the degree of rocking of the lever 38 as the distance of the stud 45 from the rocking axis of the lever may vary.

With this arrangement it is apparent that at each rotation of the shaft 24 the detent 36 is moved into engagement with a notch in the adjusting collar 35 and then retracted therefrom, the detent remaining in engagement with the collar a sufficient period to permit a predetermined turning of the spindle 20 relative thereto so that the collar is given a slight adjustment upward on the spindle to permit a corresponding lowering of the spindle toward the grinding member. It is also apparent that the extent of turning of the spindle in the collar 35 at each different operation or at each rotation of the shaft 24, and consequently of the spindle 20, may be varied by adjusting the fulcrum of the lever 38 toward or away from the operating stud 45 so as to vary the extent of movement of the lever at each operation and to consequently vary the period of engagement of the detent 36 with the collar. Should the adjustment be such that the permissible movement of the detent 36 toward and away from the collar 35 is less than the rocking movement of the lever

38, the yielding connection between the lever and detent will permit the detent to stand at rest during a portion of the movement of the lever.

5 The degree of tilting of the frame 15 to obtain the desired beveling of a work-plate on the spindle 20 is easily determined by the provision of segmental degree plate 47 on the rear end of the bearing 17 and a stationary pointer or index finger 48 on the rear end of the frame arm 8 in register with said plate.

10 The frame 6 which is mounted for rotary adjustment in the base portion 3 is clamped in adjusting position, in the present instance, by the manipulation of a cam lever 49, which is carried by a shaft 50 journaled in the base 3, and has an eccentric or cam portion 51 in coaction with a shoulder on 15 the lower extended end of the frame bearing 5.

15 The grinding member 32, in the present instance, is of disk form and is carried at the upper end of a vertical shaft 52 that is journaled in the upright 2 of the base, and 20 has a belt pulley 53 which may be belted to any suitable source of power. A second pulley 54 on this shaft is connected by a belt 55 to the pulley 14 on the shaft 13 to effect a 25 driving of the latter shaft from the shaft 52.

30 In the operation of my machine the operator clamps or fixedly attaches a work-plate *a* to the holding means 29 of the spindle 20, in the present instance by exhausting the air from said means to create a holding suction on the plate, and, if the tilting frame 15 has not already been placed at the proper 35 inclination to impart the desired bevel to the edge of the work-plate when brought in contact with the driving or abrading member 32, the bearings 16 and 17 are loosened to permit of such adjustment and then tightened to firmly clamp the frame 15 in desired adjusted relation to the frame 6.

40 The automatic adjusting means for the collar 35 may also be adjusted, as hereinbefore described, to cause said collar to have the desired extent of turning relative to the spindle 20 at each rotation of said spindle.

45 The desired templet 10 having been placed on the shaft 9, the power is thrown on to cause a driving of both the grinding wheel and the main shaft 13 of the work holding and driving means from which rotation is 50 communicated at like speed to both the templet and spindle 20. If the templet is of other than true circular form the spindle and work will have the desired vertical movements imparted thereto to permit or 55 cause the edge of the work-piece, which is of a shape corresponding to the templet, to remain in contact with the grinding member as the work-piece is rotated, it being understood that the templet acts upward 60 against the collar 34, which has a ball bear-

65 ing thrust against the adjusting collar 35, so that the major portion of the weight of the spindle and parts carried thereby is borne by the templet rather than being exerted on the work-plate *a*. As the grinding 70 progresses and the edge of the work-plate is ground away the intermittent stopping of the rotation of the collar 35 during the rotation of the spindle 20 permits a gradual intermittent lowering of the spindle through 75 the collars 35 and 34 sufficient to compensate for the grinding away action. If it is desired to bevel the edge of a circular work-piece, it is only necessary to place a circular templet of desired size on the shaft 9 80 and to adjust the frame 15 at the desired angle. The mounting of the frame 6 for horizontal rotary movements on the base upright 3 permits a turning of the frame 6 and parts carried thereby to move the spindle 20 from over the grinding member 32. 85

90 I wish it understood that my invention is not limited to any specific construction, arrangement or form of the parts, as it is capable of numerous modifications and changes without departing from the spirit of the claims.

95 Having thus described my invention, what I claim as new, and desire to secure by Letters Patent, is—

1. In a machine of the class described, a tiltable frame, a non-tiltable frame, a work carrying spindle carried for rotary and axial movements by the tiltable frame, a rotatable templet carried by the non-tiltable 100 frame and acting on a portion of the spindle to impart predetermined axial movements thereto when the templet is rotated, and means for imparting predetermined rotation to the spindle and templet. 105

2. In a machine of the class described, an axially and rotatably movable work carrying spindle, means carrying the spindle for tilting movements, a rotatable templet coaxial with the tilting axis of the spindle 110 and acting on a part of the spindle to control the axial movements thereof, and means for imparting rotation to the spindle and templet.

3. In a machine of the class described, a 115 frame mounted for tilted adjustment, a work carrying spindle journaled in the frame for axial and rotary movements and adapted to present the edge of a work-piece carried thereby to a grinding member for beveling purposes, a rotatable templet coaxial with the tilting axis of the spindle and acting on the spindle to control its axial movements, and means for imparting predetermined rotation to the spindle and templet. 120

4. In a machine of the class described, a frame, a work-carrying spindle journaled therein in substantially upright position and caused to exert a downward pressure toward its lower work-carrying end, a rota- 130

table templet acting to support the spindle and control its axial movements, and means for imparting predetermined rotation to the spindle and templet.

5. In a machine of the class described, a grinding medium, a horizontally adjustable frame, a frame carried by the first frame for vertical tilting movements, a work-carrying spindle journaled in the tilting frame for 10 tilting and axial movements relative to the working face of the grinding medium, a templet carried by the first frame and operable to control the axial movements of the spindle, and means for imparting predetermined rotation to the spindle and to the templet.

6. In a machine of the class described, a grinding medium, a frame mounted for vertical tilting movements, a work-carrying 20 spindle mounted in said frame for rotary and axial movements and adapted to be placed at a predetermined inclination to the working face of the grinding medium by an adjustment of said frame, a rotatable templet acting on the spindle to control its axial movements and having a different axis of rotation from that of the spindle, means separate from the frame supporting the templet, and means for imparting rotation to 30 both the spindle and templet.

7. In a machine of the class described, a work-shaping member, a work-carrying spindle disposed at an incline to the working face of said member and mounted for 35 rotary and axial movements, a thrust member carried by the spindle and adjustable axially thereof, a rotatable templet coacting with the thrust member to control the axial movements of the spindle, means operable 40 to adjust the thrust member on the spindle, and means for imparting rotation to the spindle and templet.

8. In a machine of the class described, a work-shaping member, a work-carrying 45 spindle adapted to move by gravity toward said member, means guiding the spindle for axial and rotary movements, means for driving the spindle, and means operable to control the axial movements of the spindle.

- 50 9. In a machine of the class described, a work-shaping member, a work-carrying spindle movable by gravity toward said member, means guiding the spindle for rotary and axial movements, a thrust member carried by the spindle for adjustment axially thereof, a movable templet coacting 55 with the thrust member to control the axial movements of the spindle, means for moving the templet and imparting rotation to 60 the spindle, and means automatically operable during a rotation of the spindle to impart predetermined relative adjustment to the spindle and thrust member.

10. In a machine of the class described, a 65 work-carrying spindle movable axially by

gravity toward a shaping means, means guiding the spindle for axial and rotary movements, a thrust member carried for axial adjustment by the spindle, means co-acting with the thrust member to support 70 the spindle, means for imparting rotation to the spindle, and means operable to relatively adjust the thrust member and spindle to permit a predetermined axial gravity movement of the spindle. 75

11. In a machine of the class described, a work-carrying spindle movable axially by gravity toward a shaping means, means guiding the spindle for axial and rotary movements, a thrust member carried for 80 axial adjustment by the spindle, means co-acting with the thrust member to support the spindle, means for imparting rotation to the spindle, means operable to relatively adjust the thrust member and spindle to permit a predetermined axial gravity movement of the spindle, and means automatically operable during a rotation of the spindle to 85 relatively adjust the spindle and thrust member to permit a predetermined axial gravity movement of the spindle.

12. In a machine of the class described, a work-shaping member, a work-carrying spindle axially movable by gravity toward said member, means guiding the spindle for 95 rotary and axial movements, means for imparting rotation to the spindle, means supporting the spindle and having a member threaded thereon, and means operable to impart relative rotation to said spindle and 100 the threaded member of the supporting means to permit a predetermined axial lowering of the spindle.

13. In a machine of the class described, a work-shaping member, a work-carrying 105 spindle axially movable by gravity toward said member, means guiding the spindle for rotary and axial movements, means for imparting rotation to the spindle, means for supporting the spindle and having a member 110 threaded on the spindle and adapted to rotate therewith, and means automatically operable during a rotation of the spindle to periodically coact with the member of said supporting means to cause it and the spindle 115 to have relative rotation to permit a predetermined lowering of the spindle.

14. In a machine of the class described, a work-shaping member, a work-carrying spindle axially movable by gravity toward 120 said member, means forming a tiltable bearing for the spindle and permitting it to have rotary and axial movements, means for imparting rotation to the spindle, a thrust member threaded on the spindle, means having a part coacting with the thrust member to support the spindle, and means connected to the spindle driving means and operable to periodically engage the thrust member and hold it against movement with the spin- 125 130

dle to effect a relative axial adjustment of the spindle therethrough.

15. In a machine of the class described, a work-shaping member, a frame, a shaft journalized in said frame, a templet carried by said shaft, a tiltable frame carried by said first frame, a work-carrying spindle axially movable by gravity toward the work-shaping member and mounted in said 5 tiltable frame for rotary and axial movements, means carried by the spindle and coacting with the templet for controlling the vertical movements of the spindle, and means for imparting rotation to the templet 10 shaft and spindle.

16. In a machine of the class described, a frame, a horizontally disposed shaft journalized therein, a templet carried by said shaft, a frame tiltably carried by said first 20 frame, a work-carrying spindle mounted for axial and rotary movements in the tiltable frame and having its inclination varied by an adjustment of the tiltable frame, means on the spindle coacting with the templet to 25 control the axial movements of the spindle, and means operable to adjust the templet coacting means axially of the spindle, and means operable to impart rotation to the templet shaft and spindle.

30 17. In a machine of the class described, a frame mounted for horizontal adjustment, a shaft journalized therein, a templet carried by said shaft, a work-carrying spindle mounted in said frame for rotary and axial 35 gravity movements relative thereto, said spindle having a part coacting with the templet to control the vertical movements of the spindle, and means for imparting rotation to the templet shaft and spindle.

40 18. In a machine of the class described, a work-shaping member, a horizontally adjustable frame, a frame carried for tilting adjustment by said first frame, a spindle mounted in the tilting frame for rotary 45 movements and for gravity axial movements toward the shaping member, the inclination of the spindle being varied by a tilting adjustment of the tilting frame, a rotatable templet carried by said first frame 50 in coaction with a part of the spindle to control the axial movements of the spindle,

and means for imparting rotation to the templet and spindle.

19. In a machine of the class described, a work-shaping member, a work-carrying 55 spindle, means carrying the spindle for rotary and axial movements, the axial movements being toward and away from said member, means urging an axial movement of the spindle toward the member, means 60 for imparting rotation to the spindle, and templet means coacting with the spindle to control the axial movements thereof.

20. In a machine of the class described, a work-shaping member, a work-carrying 65 spindle, means carrying said spindle for rotary movements, for axial movements toward and away from said member and for transverse movements relative to said member, means urging an axial movement of the 70 spindle toward said member, means for imparting rotation to the spindle, and templet means coacting with the spindle to receive the normal axial spindle pressure and adjustable to permit a movement of the spindle 75 toward the work-shaping member to compensate for wear.

21. In a machine of the class described, a work-shaping member, a work-carrying spindle, means carrying the spindle for 80 axial movements toward and away from said member for rotary movements and for tilting movements, means carried by the spindle for adjustment axially thereof, means urging an axial movement of the 85 spindle toward the work-shaping member, a rotatable templet coacting with the means carried by the spindle for resisting a movement of the spindle by said urging means, means for imparting rotation to the spindle 90 and simultaneously therewith rotation to the templet to control the axial movements of the spindle, and means automatically operable to adjust the templet coacting means 95 axially of the shaft to permit an axial movement of the shaft independent of that which is permitted by the templet to compensate for wear.

In testimony whereof, I have hereunto signed my name to this specification.

ALBERT F. JOHNSTON.
